UNITED STATES PATENT OFFICE

WILLIAM E. KRUEGER, OF SOUTH MILWAUKEE, WISCONSIN, ASSIGNOR TO LINE MATERIAL COMPANY, OF SOUTH MILWAUKEE, WISCONSIN, A CORPORATION OF DELAWARE

REFLECTOR-ATTACHING STRUCTURE FOR LAMPS

Application filed October 30, 1929. Serial No. 403,414.

This invention relates to reflector attaching structures for lamps.

Objects of this invention are to provide a novel form of reflector attaching structure for lamps which is so constructed that the reflector may be very readily attached or detached from the body portion, which is provided with means for preventing inadvertent detachment of the reflector, and which requires no tools whatsoever for either attaching or detaching the reflector.

Further objects are to provide a reflector attaching structure which is equipped with means for preventing rattling of the reflector even when the device is subjected to severe jars, which somewhat yieldingly holds the reflector in its correct position centrally of the body portion of the reflector receiving structure, and which positively locks the reflector to the body portion so that it cannot be detached without first detaching a latching member.

Further objects are to provide a reflector attaching structure which is so made that threads are provided in the body portion which receives the reflector and a novel spring construction is provided for the reflector in the place of cooperating threads, such spring or yielding construction not only cooperating with the threaded portion of the body of the device, but also preventing rattling of the reflector and serving a still further purpose of providing a very simple form of lock or latching means to prevent inadvertent detachment or unscrewing of the reflector.

Further objects are to provide a construction which is so made that an unskilled laborer may easily detach or attach a reflector, in which adequate protection is afforded all live parts of the lamp receiving body portion, in which it is impossible to screw the reflector beyond a certain predetermined point and which therefore permits the use of a metal reflector with absolute assurance that no possible short-circuiting or other harmful electrical connections can be inadvertently made during the assembly or removal of the reflector.

Embodiments of the invention are shown

in the accompanying drawings, in which:

Figure 1 is a side elevation, partly in section, of the apparatus.

Figure 2 is a sectional view on the line 2—2 of Figure 1.

Figure 3 is a fragmentary sectional detail showing a modified form of the invention.

Referring to the drawings, it will be seen that a body portion 1 has been provided, and that this body portion is carried in any suitable manner, as by means of the canopy 2. The body portion may be made of porcelain or other material as desired, and is provided with a downwardly projecting cylindrical flange or member 3, as shown in Figure 1. The body portion is also provided with any suitable means for receiving a lamp, not shown. For example, it may be provided with yielding contact strips or fingers 4 between which the prongs of the lamp may be inserted. The contact strips 4 are connected to wire receiving members or terminals 5.

In the form of the invention shown in Figure 1, it will be seen that the downwardly projecting portion of the body 1 carries a sleeve 6 which may be formed of metal and which constitutes an extension of the downwardly projecting flange 3. This metal sleeve may be held in place in any suitable manner, as by means of the screws 7, which pass through the flange 3 and are threaded into the extension or sleeve 6. This sleeve 6, it is to be noted, is internally threaded, as indicated at 8, and it is preferable to form these threads with a somewhat round bottom.

The reflector 9 may be of metal, if desired, and is provided with a cylindrical shank 10 adapted to fit within the extension or sleeve 6 of the downwardly projecting flange 3, as shown in Figures 1 and 2.

The shank of this reflector carries a wire spring 11, which may be of bronze or other suitable material. The spring 11 surrounds the shank 10, as shown most clearly in Figure 2, and it is provided with an inwardly looped or projecting portion 12 and with a looped or rounded end 13, which also projects inwardly of the outline of the shank 10. Notches are provided for the reception of the inwardly projecting looped portions 12 and 13 of the

spring 11. One end of the spring passes inwardly of the shank through an opening 14, and is provided with an outwardly projecting finger or latching tongue 15, as shown most clearly in Figure 2. This outwardly projecting latching member or tongue extends through an opening formed in the shank 10 and is thus guided by the shank.

The pin or tongue 15 tends to move outwardly due to the resiliency of the spring, but during the initial positioning of the reflector, it merely rides within the threads or grooves 8 formed in the downwardly extending sleeve or flange. It is to be noted that the spring 11 does not extend around the shank in a single plane, but due to the openings which receive the projecting portions, the spring in reality is spirally wound or positioned about the shank. The spring 11 is not truly circular, but is so shaped that the intermediate portions thereof between each end and the inwardly projecting part 12 tend to bow outwardly and cause a binding action between the spring and the sleeve 7.

This construction prevents rattling of the reflector and at the same time aids in maintaining a central position for the reflector with respect to the body portion, even when the sleeve 6 is slightly larger than the shank or cylindrical portion 10 of the reflector.

The assembling of this spring is very easy to follow, for, from a reference to Figure 2, it will be seen that the locking or latching end of the spring may be inserted through the opening 14, and thereafter the locking or latching projection or tongue 15 may be passed outwardly through its corresponding opening in the shank 10. It is then a simple matter to slip the projecting portions 12 and 13 into their appropriate notches or openings in the shank 10, so that the spring occupies the position shown at Figures 1 and 2.

In using the apparatus, the reflector is merely screwed into place, the spring fitting within the threads 8 and traveling along such threads until a predetermined point is reached. This predetermined point for arresting further motion of the reflector is obtained by providing an opening 16 in the sleeve 6, into which the projecting tongue 15 snaps and thus locks the reflector against rotary motion in either direction. It is to be noted that the projecting finger or tongue 15 therefore limits the inward screwing of the reflector, and in addition locks the reflector against unscrewing. The reflector, therefore, cannot be inadvertently detached from the body portion.

In order to permit the removal of the reflector when it is desired, means are provided for unseating the tongue or finger 15 of the spring. This means may consist of a small plunger 17 which is carried at the end of a leaf spring 18 secured to the body portion as

shown in Figure 2. The plunger 17 is positioned within the hole or notch 16 and is preferably provided with a slightly enlarged inner end, which seats on a corresponding shoulder of the hole 16, although, of course, this construction could be varied without departing from the spirit of this invention. As a matter of fact, any other unseating means for pressing the tongue 15 inwardly could be employed. It is, also, of course, possible to dispense with the plunger 17 and allow the workman to depress the tongue 15 by means of a punch or other instrument of this kind, although the construction illustrated is very much preferred.

It may be found desirable to dispense with the metallic extension sleeve 6 which forms an extension of the flange 3 of the body portion. This could readily be accomplished, as shown in the modified form of the invention illustrated in Figure 3, by forming the flange 3' of the body portion 1' of greater length than that shown in Figure 1, and by forming the internal threads 8' directly in this flange. The operation of the apparatus is identically the same as that previously described.

It is to be understood that although the spring has been shown as carried by the reflector and as spirally positioned on the shank of the reflector, that the threads could be formed in the reflector and the spring structure could be carried by the body portion, provided, of course, that the positive interlocking of the spring with the threads is obtained, and provided also that the latching is secured by a projecting and yielding tongue or latching member formed on the spring.

It will be seen that a very simple reflector attaching structure has been provided by this invention which is so made that an easily formed and assembled spring, carried by the reflector, cooperates with a threaded portion of the body which receives the reflector.

Although this invention has been described in considerable detail, it is to be understood that such description is intended as illustrative rather than limiting, as the invention may be variously embodied and is to be interpreted as claimed.

I claim:

1. A lamp receiving structure comprising two members, one of said members being a body portion and the other of said members being a reflector, each of said members having a cylindrical portion, one of said cylindrical portions having threads formed therein, and the other of said cylindrical portions having a spirally arranged spring adapted to engage said threads.

2. A lamp receiving structure comprising two members, one of said members being a body portion and the other of said members being a reflector, each of said members having a cylindrical portion, one of said cylindrical portions having threads and having a hole

formed therein, and the other of said cylindrical portions having a spirally arranged spring adapted to engage said threads, said spring having a projecting portion adapted to enter said hole to prevent unscrewing of said members.

3. A lamp receiving structure comprising a body portion having a threaded part, a reflector adapted to be received by said body portion, and a resilient member having a spiral shape carried by said reflector and interlocking with the threads of said body portion.

4. A lamp receiving structure comprising a body portion having a threaded part, a reflector adapted to be received by said body portion, and a resilient member having a spiral shape carried by said reflector and interlocking with the threads of said body portion, said resilient member yieldingly binding against said body portion and said reflector.

5. A lamp receiving structure comprising a body portion provided with a cylindrical flange having threads formed therein, a reflector having a cylindrical portion adapted to be received by said flange, a spirally arranged spring carried by the cylindrical portion of said reflector and cooperating with said threads, said spring having projecting portions and said reflector having apertures for the reception of said projecting portions to thereby hold said spring in its spiral position, said spring binding against said body portion and said reflector to prevent rattling of said reflector.

6. A lamp receiving structure comprising a body portion provided with a cylindrical flange having threads formed therein, a reflector having a cylindrical portion adapted to be received by said flange, a spirally arranged spring carried by the cylindrical portion of said reflector and cooperating with said threads, said spring having projecting portions and said reflector having apertures for the reception of said projecting portions to thereby hold said spring in its spiral position, said spring tending to assume a shape other than circular, whereby said spring will bind against said reflector and said body portion.

7. A lamp receiving structure comprising a body portion having a projecting cylindrical flange provided with threads, a reflector having a cylindrical flange adapted to be received by the flange of said body portion, a spring carried by said reflector and adapted to fit within said threads, the flange of said body portion having a hold thereon, and said spring having a projecting latching tongue adapted to enter said hole to prevent inadvertent unscrewing of said reflector.

8. A lamp receiving structure comprising a body portion having a projecting cylindrical flange provided with threads, a reflector having a cylindrical flange adapted to be

received by the flange of said body portion, a spring carried by said reflector and adapted to fit within said threads, the flange of said body portion having a hold thereon, and said spring having a projecting latching tongue adapted to enter said hole to prevent inadvertent unscrewing of said reflector, and means for forcing said projecting tongue out of said hole.

9. A lamp receiving structure comprising a body portion provided with a downwardly extending flange having threads formed therein, a reflector having a cylindrical shank, a spirally arranged spring carried by the cylindrical shank of said reflector, said cylindrical shank having apertures, and said spring having projecting portions fitting within said apertures, said spring having a projecting latching tongue, the flange of said body portion having a hold adapted to receive said latching tongue, and a plunger carried by said body portion and adapted to move said projecting tongue from said hole when said plunger is depressed.

In testimony whereof, the signature of the inventor is affixed hereto.
